(57) CLAIM

The ornamental design for a pool brush head, as shown and as described.

DESCRIPTION

FIG. 1 is a perspective view showing my new design.

FIG. 2 is another perspective view thereof.

FIG. 3 is a front view thereof.

FIG. 4 is a rear view thereof.

FIG. 5 is a left end view thereof.

FIG. 6 is a right end view thereof.

FIG. 7 is a top view thereof; and,

FIG. 8 is a bottom view thereof.

The broken-lines in the drawings are for illustrative purposes only and forming no part of the claimed design.
